SIDETRACKING TOOL

Walter Brauer, Houston, Tex.

Application March 16, 1936, Serial No. 69,079

7 Claims. (Cl. 255—1)

The invention relates to a sidetracking tool and particularly of the type which is used in sidetracking a well bore.

It is often necessary that the direction of a well bore be sidetracked so that it may penetrate desirable formations and with a view of avoiding some obstruction. In a majority of instances the well bore contains a string of pipe or casing which is usually of steel and if the elevation at which the side tracking is to occur is within this well casing a window or opening must be drilled through the steel pipe.

It seems obvious that considerable difficulty is encountered in diverting the milling tool so as to cut the window or opening in the steel pipe.

It is desirable also to orient the window which is being formed so that the sidetracking will occur in the desired direction. This is particularly true where some undesirable formation is to be avoided and the direction of the well diverted to a predetermined location. The present invention directs itself to an assembly of parts which are so constructed and arranged that they may be lowered into the well bore and a complete sidetracking operation performed thereby. It is one of the objects of the invention to provide an anchor, which can be oriented in a well bore to serve as a support for a sidetracking tool assembly.

Another object of the invention is to provide in combination with an anchor a diverting mandrel which will serve to move the milling tool into an eccentric position in the pipe to be milled.

Another object of the invention is to provide an assembly made up of a tapered mandrel, eccentric bushing and a milling tool which can be lowered into the well bore as a unit.

Still another object of the invention is to provide a centering device for a milling tool diverting mandrel so that the tool will be forced against the pipe to be milled while the mandrel is maintained in a centered position.

Other and further objects of the invention will be readily apparent when the following description is considered in connection with the accompanying drawings herein:

Fig. 1 is a central vertical section of the upper end of an assembly embodying the invention and arranged in operating position in a well bore.

Fig. 2 is the lower end of the assembly shown in Fig. 1 and illustrating the anchor in the pipe.

Fig. 3 shows the anchor of Fig. 2 in position before it is set.

Fig. 4 is a section taken on the line 4—4 of Fig. 2.

Fig. 5 is a section taken on the line 5—5 of Fig. 1.

Fig. 6 is a side elevation of the eccentric bushing and the centering device mounted upon the mandrel.

Fig. 7 is a section taken on the line 7—7 of Fig. 6.

Fig. 8 is a sectional view of the pipe being milled with the sidetracking assembly shown therein.

The pipe through which the sidetracking operation is to occur is seen in Fig. 1 and illustrated generally at 2. It may be any form of well casing.

When it is determined that a sidetracking operation is to be performed, the direction is ascertained and the elevation at which the window 3 is to be formed in the pipe 2 is also determined. With this information at hand, an operating string of pipe 4 is run into the well as seen in Fig. 3, and carries on its lower end the anchor assembly 6. This assembly includes the body 5 which is tapered at 7 and is formed with dovetailed construction 8 which is to receive the jaws 9 of a slip assembly which are slidably mounted on the body 5.

The body 5 is provided with openings 11 which are arranged to receive the spring fingers 12 having the hooked ends 13 thereon, so that these fingers tend to hold the jaws 9 in retracted position as seen in Fig. 3. A collar 15 is slidable on the lower cylindrical portion of the body 5 and is cut out at its upper end at 16 to fit over the ends 13 of the fingers 12 to hold them in position in the openings 11.

A spring 18 normally urges the collar 15 upwardly and this spring abuts against the lower end 19 on the body 5.

A plurality of spring arms 20 extend outwardly from the collar 15 and scrape against the inside of the pipe 2 as the anchor is lowered. These arms click past the couplings 21 on the pipe 2 until the anchor has been lowered to the desired elevation, whereupon an upward pull on the operating string 4 brings the arms into a coupling opening as seen in Fig. 2 so that the locking collar 15 is held stationary while the body 5 continues to be raised. This releases the fingers 12 and the jaws 9 from their locked position. The next operation is to again set down on the operating string 4 rather sharply so that the inertia of the jaws 9 will cause them to travel up on the tapered face 7 and set against the inside of the pipe 2 as seen in Fig. 2. This locks the anchor assembly 6 in a definite position in the well pipe.

It will be understood that prior to the setting operation that the operating string 4 had been properly oriented so that the rib 25 in the inside passage 26 of the body 5 was facing in a predetermined and desired direction for a purpose which will be later described. The setting string 4 is then unscrewed from the socket 28 in the upper end of the body 5 so that the anchor remains in the well bore.

10 The sidetracking tool is so constructed and arranged that it can be lowered into the well bore at the same time as the milling tool and in Fig. 1 the operating string or drill pipe is seen at 30. This pipe has threaded to its lower end a collar 31 which may be of any desired length and has the milling tool or cutter 32 attached to its lower end. This milling cutter is of a construction such that it has teeth 33 on the lower face thereof which are arranged to cut into the wall of the pipe 2 in order to form the window 3. In Fig. 1 the window 3 is practically completed with the collar 34 of the milling cutter projecting out through the side of the pipe 2.

It seems obvious that this milling cutter 32 must be moved laterally in the inside passage 35 of the pipe 2 so that the window 3 will be cut in the side wall. To accomplish this, the sidetracking tool is provided with a mandrel 36. This mandrel is best seen in section in Fig. 5 and has 20 a flat tapered or beveled face 37 which tapers downwardly and outwardly as regards the back face 38 of the mandrel.

As seen in Fig. 1, this mandrel 36 has been telescoped upwardly inside of the milling tool 32 and the collar 31 and carries an extended head stop piece 39 thereon which is suitably affixed after the mandrel has been passed up into the collar and serves to prevent the mandrel from dropping out of the collar, or passing below the upper end 40 or the bushing 41.

The bushing 41 is positioned in a recess 42 in the lower end of the collar 31 and the upper inside portion of the milling tool 32, and is rotatably mounted therein but is fixed against longitudinal movement relative to the collar and bit 45 by being held firmly in position by the connection between the milling cutter 32 and the collar.

This bushing is best seen in section in Fig. 5 and has an eccentric passage 42 therein which receives the mandrel 36. This passage has flat sides at 43 so it is non-rotatable with respect to the mandrel but the mandrel may slide vertically through the passage 42. A suitable passage for fluid 44 is provided in the bushing.

55 As seen in Fig. 5 a plurality of antifriction rollers 46 are carried on the side of the bushing 41 which abut against the face 47 inside of the collar 31 and milling tool 32. The pressure of side-tracking the cutter 32 is transferred from the face 37 of the mandrel to the bushing 41 by the contact face 45, and then by the antifriction rollers 46 to the inside surface 47 of the cutter or collar.

In view of the fact that the opening 42 in the bushing is eccentric causes the bushing to force the cutter 32 off center as the bushing slides downwardly along the tapered face 37. The mandrel and bushing will remain stationary and as the stem 30 imparts rotation to the cutter 32 the cutter will be forced gradually against the wall of the pipe to form the window 3.

It is, of course, necessary that the mandrel 36 be maintained in a center position in the pipe 2 in order to cut the window. To accomplish this, a centering sleeve 60 is shown as carried by the

lugs 61 which project from the lower end of the bushing 41. The side plates 62 are pivoted on the pins 63 on the lugs 61 and have their lower ends connected to the sleeve 60 so that the sleeve 60 will move vertically with the bushing 41, and, of course, with the cutter 32 so that it is closely adjacent the area being cut to avoid imparting excessive bending stresses to the mandrel 36.

As seen in Fig. 1, the pin 63 is mounted in a slot 64 in the lugs 61 so that the bushing 41 may 10 move laterally without carrying the sleeve 60 with it. The purpose of the sleeve 60 is to hold the mandrel in central position in the pipe 2 and it is intended that it will be of sufficient strength to avoid bending when the milling cutter is ro- 15 tated.

In order to anchor the lower end of the mandrel 36 in position, and in order to orient it so that the window 3 will be formed in the proper direction, the lower end of the mandrel 36 is 20 formed with a reduced section 65 which is arranged to pass into the opening 26 in the anchor assembly, as seen in Fig. 2. The end 65 is formed with a groove 66 which is complementary with the rib 25. It will be seen that if the anchor 25 has been positioned in the well, as seen in Fig. 3, and the operating string 4 removed, that then the milling tool assembly can be run into the well and the lower end 65 of the mandrel will come in contact with the body 5 of the anchor. A slight 30 rotation thereof will cause the groove 66 and rib 25 to move into alignment so that the mandrel will slip down into the opening 26. This drop of the milling tool assembly into the opening 26 indicates to the operator that he is properly 35 oriented and set and that he can now begin lowering the drill pipe 30 and rotating the same in order to cut the window 3.

The passage 68 is formed through the mandrel in order to permit the desired circulation of fluid 40 during the milling operation, or a circulation can be maintained through the passage 44 if desired.

Broadly the invention contemplates a sidetracking assembly which can be anchored for orientation in the well bore in order to form an 45 opening in the desired direction and at the desired elevation.

What is claimed is:

1. A sidetracking tool of the character described comprising an anchor to be set in the well bore, a tapered mandrel carried by said anchor, an eccentric bushing slidable on said mandrel, and a milling cutter rotatably carried by said bushing, whereby relative sliding movement between said bushing and mandrel moves said mill- 55 ing cutter laterally.

2. A sidetracking tool of the character described comprising an anchor to be set in the well bore, a tapered mandrel carried by said anchor, an eccentric bushing slidable on said mandrel, a 60 milling cutter rotatably carried by said bushing, whereby relative sliding movement between said bushing and mandrel moves said cutter laterally, and means carried by said bushing to center said mandrel in the well bore.

3. The combination with a pipe in a well bore which is to have a window drilled therein of a wedge mandrel, means to anchor said mandrel in said pipe, a milling tool disposed eccentrically over said mandrel to be wedged against said pipe 70 thereby so that rotation of said tool will cut said pipe, and means carried by said tool to center said mandrel in said pipe.

4. A milling tool for sidetracking through well pipe comprising an operating string of pipe, a

milling cutter on the lower end thereof, and an eccentric bushing rotatably carried thereby.

5. A milling tool for sidetracking through well pipe comprising an operating string of pipe, a milling cutter on the lower end thereof, an eccentric bushing rotatably carried thereby, and a mandrel to receive said bushing to hold said cutter eccentrically in the pipe.

6. A milling tool for sidetracking through well pipe comprising an operating string of pipe, a milling cutter on the lower end thereof, an eccentric bushing rotatably carried thereby, a man-

drel to receive said bushing to hold said cutter eccentrically in the pipe, and a mandrel centering member below said tool.

7. A sidetracking assembly comprising an anchor member, a tapered mandrel supported thereby, a centering sleeve slideable on said mandrel, an eccentric drive bushing also slideable on said mandrel, and a milling cutter to be driven into the pipe to be cut by said bushing sliding on the taper of said mandrel.
